Primary Examiner — Susan Moon Lee(74) *Attorney, Agent, or Firm* — Dorsey & Whitney LLP(57) **CLAIM**

I claim the ornamental design for a dispensing device for animals.

DESCRIPTION

FIG. 1 is a top-left perspective view of a dispensing device for animals.

FIG. 2 is a right-side elevation view of the dispensing device for animals of FIG. 1.

FIG. 3 is a left-side elevation view of the dispensing device for animals of FIG. 1.

FIG. 4 is a front elevation view of the dispensing device for animals of FIG. 1.

FIG. 5 is a rear elevation view of the dispensing device for animals FIG. 1.

FIG. 6 is a top plan view of the dispensing device for animals of FIG. 1; and,

FIG. 7 is a bottom plan view of the dispensing device for animals of FIG. 1.
